CLAIM

The ornamental design for an injection tube support apparatus, as shown.

DESCRIPTION

FIG. 1 is a perspective view an injection tube support apparatus showing my new design;
 FIG. 2 is a first side view thereof;
 FIG. 3 is a second side view thereof;
 FIG. 4 is a front view thereof;
 FIG. 5 is a back view thereof;
 FIG. 6 is a top plan view thereof; and,
 FIG. 7 is a bottom plan view thereof.
